UNITED STATES PATENT OFFICE.

JOHN B. LUKOMSKI AND ANTHONY LUKOMSKI, OF DETROIT, MICHIGAN.

DESIGN FOR A WATER-CLOSET-BOWL FLOOR-PLATE.

52,059.

Specification for Design.

Patented May 28, 1918.

Application filed January 19, 1916. Serial No. 73,054. Term of patent 14 years.

To all whom it may concern:

Be it known that we, JOHN B. LUKOMSKI and ANTHONY LUKOMSKI, citizens of the United States of America, residing at Detroit, in the county of Wayne and State of Michigan, have invented a new, original, and ornamental Design for a Water-Closet-Bowl Floor-Plate, of which the following is a specification, reference being had therein to the accompanying drawing, forming part thereof.

Figure 1 is a plan view of the water closet bowl floor plate, and

Fig. 2 is a cross section of the same.

What we claim is:—

The ornamental design for a water closet bowl floor plate, as shown.

JOHN B. LUKOMSKI.
ANTHONY LUKOMSKI.
